UNITED STATES PATENT OFFICE.

RICHARD F. VAN METER, OF MINNEAPOLIS, MINNESOTA.

SPARK-GAP DEVICE.

1,341,348.

Specification of Letters Patent. Patented May 25, 1920.

Application filed May 26, 1919. Serial No. 299,717.

To all whom it may concern:

Be it known that I, RICHARD F. VAN METER, a citizen of the United States, residing at Minneapolis, in the county of Hennepin and State of Minnesota, have invented certain new and useful Improvements in Spark-Gap Devices, of which the following is a specification.

My invention relates to spark gap devices and an object in general is to provide a device which will act to intensify the spark which is produced by the usual spark plugs used in cylinders of internal combustion engines. The weaker the spark produced by the spark plugs, the slower will be the propagation of flame in the explosive mixture, which necessitates a greater advance to the spark. On the other hand, the hotter the spark, the less early it must occur in advance of dead center, since there is a direct relation between the heat of the spark and the speed of flame propagation in the mixture. By bringing the timing of the spark nearer dead center, more power is generated in the forward direction to drive the pistons and less fuel is required. In order to intensify the spark in the combustion cylinder I employ a spark gap device which produces a spark in the circuit leading to the spark plug, this spark acting to intensify and build up the spark produced by the spark plug. Since this preliminary spark is produced outside of the combustion cylinder, where it might meet with objection from the fire underwriters, a special object of my invention is to provide a device which cannot produce an explosion if it should be surrounded by an explosive mixture. A further object is to construct a spark gap device so that the spark may be readily observed and at the same time will not prevent the entrance of air to the gap in which the spark is produced. In this way the strength of the preliminary spark is maintained on account of there always being a sufficient supply of oxygen from the air, while the driver can tell at a glance whether or not the spark is being produced.

The full objects and advantages of my invention will appear in connection with the detailed description thereof and the novel features embodied in my inventive idea will be particularly pointed out in the claims.

Referring to the accompanying drawings,

which illustrate the application of my invention in one form, —

Figure 1 is a view in perspective showing my device attached to the dash of an automobile. Fig. 2 is a face view partly in section of my device. Fig. 3 is a view on the line 3—3 of Fig. 2 looking in the direction of the arrow. Fig. 4 is a view on the line 4—4 of Fig. 2 looking in the direction of the arrow.

Referring to the drawings, 10 designates the customary coil box, which is secured to the dash of an automobile with wires 12 leading from a source of electrical energy to the primary coils in the coil box. The secondary or high tension coils in the coil box are customarily connected to the binding posts 14. Instead of connecting these binding posts directly to the spark plugs as usual, the following device for producing a preliminary spark before the current reaches the spark plugs is provided. A strip 16 of insulating material such as fiber is provided with metal eyelets 18 adapted to be placed over the posts 14 and secured in place thereon by nuts 20. Since the eyelets and parts associated therewith are all alike, and since separate insulating strips may be used in connection with each binding post, a description of the parts associated with one of the eyelets will be sufficient. A terminal member or rod 22 is mounted in the strip 16 so as to be in contact with an eyelet 18 and the outer end of this rod is flattened so that the position of the rod which is screw-threaded at 23 may be readily adjusted. The inner end of the terminal 22 lies within a recess formed in the strip 16 so as to be separated by a gap 24 from a second terminal or rod 26 which is secured in the strip 16 in contact with a metal stud or rivet 28 also secured to the strip. In contact with this stud and held in place thereby is a hook 30 to which is attached in suitable manner the wire 32 leading to the spark plug 34 of the engine. A piece of insulating material 36 has openings at its ends so that it may be secured in contact with the strip 16 by the eyelet 18 and the rivet 28, and the central portion of this member 36 is enlarged and is provided with an opening which, as shown in Fig. 3, is somewhat larger than the recess containing the gap 24 and is in register with the open side of said recess. A piece of fine

wire gauze 38 is secured over the recess containing the gap 24. A convenient manner of securing the member 38 in place is shown in Fig. 3 in which this member is formed in 5 a cup shape and the outer periphery is turned out to form a marginal flange 40 which is clamped between the strip 16 and the piece 36 to securely hold this member in place. The periphery of the member 38 10 as shown in Fig. 3 is larger than the periphery of the open side of the recess whereby the liability of sparks jumping to the member 38 is avoided.

The operation and advantages of my invention will be readily understood from the foregoing description. The wire gauze prevents the passage of flame outside of the recess in which the spark is produced and avoids any objection which might otherwise 15 be made by the fire underwriters. In addition to this, the wire gauze permits entrance of air to the space in which the spark is produced and allows the spark to be readily observed. The wire gauze, therefore, has a 20 three-fold function. The construction and location of the wire gauze member is such that there is no liability of sparks jumping across to this member.

I claim:

30 1. A spark gap device for internal combustion engines comprising a strip of insulating material having a recess, two terminals having their adjacent ends spaced from each other in said recess, a piece of insulating 35 material attached to said strip and having an opening in register with the open side of said recess, a cup-shaped wire gauze mem-

ber having its periphery clamped between said strip and said piece of insulating material, and means for connecting said terminals in the circuit leading to the spark plug 40 of the engine.

2. A spark gap device for internal combustion engines comprising a support of insulating material having a recess, two terminals mounted in said support and having their adjacent ends spaced from each other 45 in said recess, a cup-shaped wire gauze member having a periphery larger than the periphery of the open side of said recess, means 50 for securing said cup-shaped wire gauze member over said open side with its bottom outward, and means for connecting said terminals in the circuit leading to the spark plug of the engine.

55 3. A spark gap device for internal combustion engines comprising a support of insulating material having a recess, two terminals mounted in said support and having their adjacent ends spaced from each other 60 in said recess, a cup-shaped wire gauze member having a periphery larger than the periphery of the open side of said recess, a piece of insulating material attached to said support and having an opening, the periphery 65 of which engages the periphery of said cup-shaped wire gauze member to hold the latter over said open side, with its bottom outward, and means for connecting said terminals in the circuit leading to the spark 70 plug of the engine.

In testimony whereof I hereunto affix my signature.

RICHARD F. VAN METER.
